Primary Examiner — Richard Edgar

Assistant Examiner — Jessica Ruth Grable

(57) **CLAIM**

The ornamental design for a undetable storage rack, as shown and described.

DESCRIPTION

FIG. 1 is a front perspective view of a undetable storage rack, showing my new design;

FIG. 2 is a rear perspective view thereof;

FIG. 3 is a bottom view thereof;

FIG. 4 is a top view thereof;

FIG. 5 is a back view thereof;

FIG. 6 is a front view thereof;

FIG. 7 is a left side view thereof; and,

FIG. 8 is a right side view thereof.

1 Claim, 8 Drawing Sheets
